By Knight Bro.

UNITED STATES PATENT OFFICE.

GEORGE W. MOULDIN, OF ST. LOUIS, MISSOURI.

OPERATING HATCHWAY-DOORS.

SPECIFICATION forming part of Letters Patent No. 224,213, dated February 3, 1880.

Application filed June 21, 1878.

To all whom it may concern:

Be it known that I, GEORGE W. MOULDIN, of the city of St. Louis, in the State of Missouri, have invented a certain new and useful Improvement in Hatch-Closers for Hoisting Apparatus, of which the following is a full, clear, and exact description, reference being had to the accompanying drawings, forming part of this specification.

10 My improvement relates to that class of hatch-closers consisting of doors hinged to the side of the hatchway, and which are automatically swung down to permit the passage of the platform and closed after its passage.

15 My invention consists in combining with the closing-doors an upwardly-extending vibrating arm, carrying an adjustable counter-balance, whose weight tends to hold the doors in the position in which they may be, (either open or closed.)

20 My improvement also consists in forming the cog-sectors with teeth in excess of the number on the rack they take into, and at the end with a tooth of greater length than the other teeth of the sectors, so that it (the elongated tooth) will not fail to receive impingement of the first tooth of the cog-rack upon the platform.

25 My invention also consists in a spring-block inserted in the face of the elongated teeth, to prevent the jar that might otherwise result from the impact of the rack against the tooth.

30 The invention also consists in arranging within recesses in the side pieces springs adapted to bear against a central lug on the rack and act as a cushion therefor.

35 Figure 1 is a perspective view of my invention. Fig. 2 is a section showing some part in side view. Fig. 3 is a view showing a spring-catch. Fig. 4 is a view of the sector, showing part in section to exhibit the spring-blocks. Fig. 5 is a section of the elongated tooth. Fig. 6 is a section of a cog-rack, showing the springs allowing end movement to relieve the jar when the rack comes in contact with a sector.

40 The guide-timbers or uprights are shown at A. B are the side pieces; C, the transom of

the platform, and D is the floor of the same. The floors of the building are shown at E.

50 The hatch or hatch-closer F F consists of two leaves, whose edges may come together on a central line from post to post, as shown, or which may each be made angular and the line of contact run obliquely to the hatchway. 55 Each of the leaves of the hatch is hinged to the floor of the building by means of a shaft, G, turning in suitable bearings G', and carrying a sheave or pulley, H or H', so that as the sheave receives a pull one-fourth of a rotation, 60 or rather more, the hatch is opened or closed, as the case may be. These sheaves are of course set out of the course of the platform, and are connected together by a belt, wire, cable, or other power-conveyer, I, that is crossed 65 or otherwise arranged to cause the simultaneous turning of the sheaves in opposite directions, to cause both leaves of the hatch to rise and fall together.

70 The sheaves H and H' are weighted on the opposite sides to the hatch, to partly counter-balance the weight of the parts of the hatch that are attached to their shafts.

75 The cable or belt I, at the ends, lap about half around the sheaves H and H', and their ends are secured fast to the sheaves, so as to impart a positive movement.

80 The sheave H, in addition to the rope or belt I, carries another cable, I', which connects it with a pulley or sheave, J, the end of the cable extending half around the sheaves, and being attached thereto, so that there is a positive simultaneous movement of the sheaves or pulleys H and J in the same direction.

85 The shaft J' of the sheave J carries a cog-sector, K, whose cogs k k' are engaged by a cog-rack, L, upon the side piece, B, of the platform. As the platform ascends and descends it gives to the sheave J a partial rotation.

90 The sheave J is preferably weighted at j to counterbalance the weight of the cog-sector K. The shaft J' carries an arm, M, on which is an adjustable weight, N, (sliding on the arm and fixed by a set-screw, n,) whose office is two-fold—first, to counterbalance the leaves F F

of the hatch-closer, and, second, to carry the leaves to their extreme positions and to hold them in such positions until again acted on by the cog-gears K L on the passage of the platform.

O is a sheave connected to the sheave H², which is fast upon the same shaft as the sheave H', by the crossed cable or belt I², whose ends are lapped around the sheave and secured thereto to secure positive simultaneous movement of the sheaves H', H², and O.

The sheave O is very similar to J, and its shaft o carries a cog-sector, K', which is engaged by a cog-rack, L', upon the side piece, B, of the platform. O' is a weight on the sheave O to counterbalance the sector K'.

It will be observed that by means of the sheaves and the connecting belts or cables I I' I² the leaves F must open and close simultaneously. All the parts are counterbalanced, so that the movements may be made with ease.

The cog-sectors K and K' are peculiar in construction, the end teeth, k, of the sector being longer than the others, and the sectors are made each with one more cog than the racks L L', so that in working the long teeth k lap over the ends of the rack. The purpose of this construction of sector is to insure the proper engagement of the racks and sectors by the end tooth of the rack first coming in contact with the long tooth of the sector and carrying the sector with it, so that the teeth of the rack and sector shall come together in the proper relative position.

The cog-racks L and L' are attached to the side pieces by bolts that pass through vertical slots l in the racks, so as to allow to the racks a limited vertical movement on the side pieces. l' l' are springs occupying recesses in the side pieces, and bearing against a central lug, l², on the back of the rack. The springs act to lessen the concussion of the sector against the rack by receiving the force of the blow and allowing the rack a limited movement with the sector until the inertia of the hatch-closing mechanism is overcome.

In addition to the spring device l' l', or in place thereof, I provide the side of the elongated tooth k, upon the side which comes in contact with the rack, with a spring-block, k², working in a recess, k³, upon a rubber or other spring, k⁴, in the recess.

The face-block k² is connected to the tooth by pins k⁵, fixed in the block and working endwise in the tooth. When the spring-block is applied to the outer tooth, then the next to that, k, should be beveled off at the same side, as shown at k², so that its end may not come in contact with the end of the second tooth of the rack, and this second tooth of the rack may be also beveled at the end, as shown, for the same purpose.

The upward motion of the leaves F in closing is checked by stop-lugs P and moving bolts Q, the latter connected to the lower ends

of a forked lever, R, whose upper end is forced outward from the hatch by a spring, S, to carry the bolts beneath the leaves F and hold them there.

Bearing against the outer side of the upper end of the lever R are the ends of two levers, T and U. The other ends of these levers are forced outward by cam-ribs V upon the side pieces, B, to draw the catches Q, from beneath the leaves, to allow them to open when the platform is approaching them, and to hold the catches back while the leaves F are again closing.

The platform is supported on a hoisting-cable, W, or raised and lowered by any suitable means.

The operation is as follows: Supposing the platform to be ascending, the cam-ribs V come in contact with the lower ends of the levers U and force back the bolts Q to allow the leaves F to open downward. Then the rack L' comes into contact with the larger tooth k' at the top of cog-sector K', and the continued ascent of the platform causes the sheaves to turn and the leaves F to open downward. Then when the platform has passed the hatchway the rack L engages the sector K, and the sheaves are all turned in an opposite direction to close the leaves F.

It will be seen that the weight N is thrown past the vertical from side to side as the hatch is opened and closed, so that by its momentum and gravity it will complete the movement of the leaves.

When the leaves have closed, the cam-ribs V pass the upper ends of levers T and the spring S projects the bolts Q beneath the free edges of the leaves, and they are held up until the return of the platform.

In descending, the sector K and rack L come into action first, to open the hatch, and it is closed by those K' L'.

The special purpose I have in elongating the outer teeth of the sectors is to prevent the teeth of the racks and sectors from becoming jammed together, from coming in contact in an improper position. This is made necessary because the platform generally has some little side play upon the guide-timbers, and consequently if the end teeth of the sector were made the same length as the others the ends of the sector-tooth might impinge against the end of the rack-tooth, and the apparatus would not operate. There would also be danger of breakage; but in my construction the rack first strikes the side of the elongated tooth, and the parts are necessarily brought into the proper relative positions.

I am aware that self-closing hatchways have been provided with vertically-arranged racks and toothed wheels to engage with such racks, and also with sheaves connected by cables and actuated by the toothed wheels. Such, therefore, I do not broadly claim; but

I claim as my invention—

1. The combination, with the hatch-closer F, sheaves H and J, and cables or belts I, of the adjustable counter-balance N and arm M, for the purpose set forth.
- 5 2. The combination, with the sheaves, belts, and weight, for use in opening and closing the hatch, of the sector K and toothed rack L, said sector having teeth in excess of the number on the rack L, and having the end teeth elongated, as and for the purpose set forth.
- 10 3. The rack having slots l for the bolts of attachment, and combined with springs v , bearing against lug l' , for the purpose set forth.
4. The sector-tooth k, provided with spring 15 bearing-face $k' k^2$, substantially as and for the purpose set forth.

GEORGE W. MOULDIN.
